UNITED STATES PATENT OFFICE.

AARON JAY, OF CHICAGO, ILLINOIS.

FURNACE.

No. 899,053.

Specification of Letters Patent. Patented Sept. 22, 1908.

Application filed July 31, 1907. Serial No. 386,450.

To all whom it may concern:

Be it known that I, AARON JAY, a citizen of the United States, residing at Chicago, in the county of Cook and State of Illinois, have 5 invented certain new and useful Improvements in Furnaces, of which the following is a full, clear, and exact description, such as will enable those skilled in the art to which it appertains to make and use the same.

10 This invention relates to improvements in furnaces of that description which are used in heating horizontal tubular steam-boilers; more particularly it relates to improvements in the furnace shown and described in Patent 15 No. 576,368, granted to me February 2, 1897. In that furnace the movable grate-bars for feeding the fuel into the fire-chamber are mounted on permanent parts of the structure.

20 In the present invention it is proposed to mount the grate-bars and the mechanism for operating the same upon a movable carriage that can be withdrawn from the fire-chamber to permit inspection, cleaning, repairs and 25 for other purposes.

The invention consists in the novel construction, combination and arrangement of parts, such as will be hereinafter fully described, pointed out in the appended claims, 30 and illustrated in the accompanying drawings.

In the drawings, in which similar reference characters designate corresponding parts, Figure 1 is a longitudinal vertical sectional 35 view of a furnace embodying the invention. Fig. 2 is a view, partly in front elevation and partly in vertical section of the same.

The horizontal tubular boiler 1 is of the ordinary type and is mounted in the usual 40 manner in the walls of the furnace above the fire-chamber 2 and the combustion-chamber 3. The two chambers are separated at their lower parts by the bridge-wall 4 and communicate at their upper parts through the 45 passage 5 over the bridge-wall. The rear end of the combustion-chamber is connected with the rear ends of the boiler tubes by the flue 6 and the front ends of the tubes open into the flue 7 leading to the uptake.

50 Above the fire-chamber 2 is the flat arch 8 extending horizontally across the chamber and projecting from the upper fixed front wall 9 of the furnace to the rear of the chamber. The arch is inclined downwardly to- 55 wards its inner end and it serves to direct the products of combustion from the fire-cham-

ber through the passage 5 into the combustion-chamber 3. The arch is composed of sections 10 held together and supported in place by the rods 11 passing through them and anchored at their ends in the side walls of the furnace. At the ends of the rods are the plates 12 between which the arch-sections are clamped together. The longitudinal contacting sides of the arch-sections, as 60 at 13, are inclined at a considerable angle from the perpendicular. By reason of the inclined sides the arch-sections nest closely together and thereby lessen the liability of cracks or openings occurring between the 65 same to permit the escape of the products of combustion from the fire-chamber through the arch. Also by means of the inclined sides any cement or filling placed between the arch-sections will be more firmly held in 70 place than if the contacting sides were vertical.

In the front part of the fire-chamber 2 is the removable carriage 14 comprising the sides 15 and the front 16. The latter forms 80 the movable lower front of the furnace and is provided with the doors 17 to permit access to the ash-pit beneath the grates. The carriage is mounted on the wheels 18 that travel on the tracks 19 laid in the floor of the fire-chamber. In bearings 20 attached to the outer face of the front 16 of the carriage is journaled the shaft 21 on which are mounted the eccentrics 22 alternately projecting in opposite directions. On these eccentrics are 85 journaled the front ends of the grate-bars 23 and held thereon by the bearing-blocks 24. The rear ends of the grate-bars are supported by the hollow box 25 mounted on the rear end of the carriage. Interposed between 90 the box and the ends of the grate-bars are the balls 26 on which the grate-bars ride when moved. The front ends of the grate-bars pass through the opening 27 in the front of the carriage so that the eccentric mechanism connected therewith is outside of the fire-chamber. Consequently such mechanism is 95 protected from the heat and the bearings are free from contact with the fuel. The grate-bars towards their rear ends are inclined 100 downwardly so that when they are oscillated by the eccentric mechanism the fuel is fed inwardly. As the eccentrics 22 alternately project in opposite directions the alternate 105 grate-bars will be oppositely oscillated, which will facilitate the movement of the fuel and the discharge of ashes.

Mechanism is provided for rotating the shaft 21 to oscillate the grate-bars. On the end of the shaft is the gear 28 engaging the worm 29 on the outer end of the shaft 30 journalized in the bracket 31 attached to the front of the carriage. On the inner end of the shaft 30 is the ratchet wheel 32 with which engages the pawl 33 carried by the arm 34 mounted on the lower end of the rod 35. The latter is connected by the strap 36 with the eccentric 37 on the shaft 38 driven by any suitable source of power. When the shaft 38 is rotated the rod 35 is reciprocated and through the pawl and ratchet mechanism an intermittent rotation is imparted to the shaft 21 to operate the grate-bars. The rod 35 is mounted on the stationary part of the furnace and when the carriage is moved outwardly the pawl 33 disengages the ratchet wheel 32, the construction of these two members being such as to permit a ready engagement and disengagement.

In the rear part of the fire-chamber 2 and immediately back of the movable carriage 25 when the latter is in place is the secondary grate 39 to receive the partly consumed and incandescent fuel from the grate-bars 23. The secondary grate is hinged to the bridge-wall 4 directly opposite to the hollow box 25 of the movable carriage. Projecting downwardly from one side of the free end of the secondary grate is the arm 40 to the lower end of which is pivoted the inner end of the rod 41. The outer end of the rod 41 passes 35 through the opening 42 in the front 13 of the movable carriage. At the outer end of the rod is the rack 43 to engage the edge of the opening 42. By means of the rod 41 the secondary grate may be agitated or dumped as 40 the occasion requires. The engagement of the rack with the edge of the opening holds the secondary grate in position. By means of the rack the elevation of the secondary grate can be regulated to meet the requirements. When the carriage is moved the rack is disengaged from the edge of the opening and the rod passes through the opening as the carriage moves outwardly.

When the carriage is in place in the fire-chamber the upper part of its front wall and the lower part of the fixed front wall 9 form a fuel reservoir above the front ends of the grate-bars 23. The reservoir communicates with the fire-chamber beneath the wall 9. 50 By means of the gate 44 adjustably mounted at the lower edge of the fixed wall 9 the communication between the reservoir and the fire-chamber can be controlled to regulate the supply of fuel that passes from the reservoir to the fire-chamber.

The operation of the furnace is as follows: The movable carriage is positioned in the fire-chamber and the secondary grate is raised and secured. After the fire has been 55 started and the reservoir filled with fuel, the

mechanism for operating the grate-bars is set in motion. Through the oscillation of the grate-bars the fuel is gradually fed from the reservoir into the fire-chamber. When the fuel becomes heated and ignition takes place it gradually moves towards the rear of the fire-chamber. The gases generated by the heat are deflected by the arch over the fire-chamber towards the passage leading into the combustion chamber. The partly 70 consumed and incandescent fuel is gradually moved to the rear and deposited in the secondary grate where it is consumed until nothing but the ashes are left. As the gases 75 pass over the secondary grate they are further heated and are ready for the further burning that takes place in the combustion-chamber. Should it become necessary to clear the coals in the secondary grate, this 80 can be easily done by the rod 41. Also by 85 means of this rod the grate can be dumped of its contents. To remove the carriage the rack 43 is disengaged from the edge of the opening 42 and the rod 41 is released, then 90 the carriage can be readily moved outwardly 95 from the fire-chamber. As the members of the pawl and ratchet mechanism can readily separate there will be no obstruction to the moving of the carriage at that point. When the carriage is returned the rod 41 is raised, 95 access to the same being had by opening the door 17, to pass through the opening 42 and operated to adjust the secondary grate.

Having thus described my invention, what I claim and desire to secure by Letters Patent is:

1. In a furnace, the fire-chamber, the combustion-chamber communicating with said fire-chamber at their upper parts, a bridge-wall separating the lower parts of the fire and combustion-chambers, a removable carriage in the front part of the fire-chamber, grate-bars movably mounted on said carriage, means for oscillating said grate-bars to feed the fuel into the fire-chamber, a secondary 105 grate hinged to said bridge-wall at the rear of said carriage to receive the fuel from the grate-bars, and a rod connected with said secondary grate for operating the same extending through and detachable from said 110 carriage so that the latter can be moved clear of the rod.

2. In a furnace, the fire-chamber, the combustion-chamber communicating with said fire-chamber at their upper parts, a bridge-wall separating the lower parts of the fire and combustion-chambers, a removable carriage in the front part of the fire-chamber, a shaft journalized in the forward part of said carriage, means for rotating said shaft, eccentrics on 125 said shaft alternately projecting in opposite directions, inclined grate-bars journaled at their upper ends on said eccentrics, a hollow box on the rear part of said carriage to form a support for the lower ends of said grate-bars, 130

balls interposed between said box and the ends of the grate-bars, a secondary grate hinged to said bridge-wall at the rear of said carriage and adjustable relatively to the lower ends of said grate-bars, a rod connected with said secondary grate extending through and detachable from said carriage so that the latter can be moved clear of said rod, and a rack on said rod to engage an edge of the frame of said carriage to hold said secondary 10 grate in its adjustments.

In testimony whereof I hereunto affix my signature in the presence of two witnesses.

AARON JAY.
